(57) **CLAIM**

The ornamental design for a worklight, as shown and described.

DESCRIPTION

FIG. 1 is a front, top and right-side perspective view of a worklight showing our new design;

FIG. 2 is a front view thereof;

FIG. 3 is a rear view thereof;

FIG. 4 is a top view thereof;

FIG. 5 is a bottom view thereof;

FIG. 6 is a right-side view thereof;

FIG. 7 is a left-side view thereof;

FIG. 8 is a cross-sectional view taken along line 8-8 in FIG. 2, in which the internal mechanism is omitted; and, FIG. 9 is a front, bottom and left-side perspective view thereof without a clamp.

The broken lines shown represent unclaimed subject matter of the worklight and form no part of the claimed design.

1 Claim, 8 Drawing Sheets
